EXPOSURE METER

Toshihiko Sakow, Fort Lee, N.J., assignor to Weston Instruments, Inc., Newark, N.J., a corporation of Delaware

Filed Feb. 5, 1968, Ser. No. 10,425

Term of patent 14 years

(Cl. D61—1)

FIG. 1

FIG. 2

FIG. 3

FIGURE 1 is a front view of an exposure meter illustrating my new design;

FIGURE 2 is a rear view of the exposure meter shown in FIGURE 1; and

FIGURE 3 is a side view of the exposure meter shown in FIGURE 1.

I claim:

The ornamental design for an exposure meter, substantially as shown.
